UNITED STATES PATENT OFFICE.

IDA M. ARGO, OF DALLAS, TEXAS.

CATAMENIAL BANDAGE.

979,730.

Specification of Letters Patent. Patented Dec. 27, 1910.

Application filed March 10, 1910. Serial No. 548,387.

To all whom it may concern:

Be it known that I, Ida M. Argo, citizen of the United States, residing at Dallas, in the county of Dallas and State of Texas, have invented certain new and useful Improvements in Catamenial Bandages, of which the following is a specification.

This invention has relation to bandages and particularly to that class known as catamenial sacks.

The object of the invention is to provide a bandage comprising a supporting member, a water-proof pad, and a sack, the member and pad having particular shapes and stitched in a particular manner whereby the member and pad adapt themselves to the parts to which they are applied and retain their proper shape.

Another feature resides in the means for positioning and supporting the bandages on the body of the wearer whereby the bandage is self adjusting to different positions assumed by the wearer and also whereby all obtrusions or wrinkles which might detract from the neat appearance of the overlying clothing of the wearer, are obviated.

Finally the object of the invention is to provide a device of the character described that will be durable, efficient, simple and comparatively inexpensive to construct.

With the above and other objects in view, the invention has relation to certain novel features of construction and operation, an example of which is described in this specification and illustrated in the accompanying drawings, wherein:

Figure 1. is a perspective view of the bandage in the position it occupies when on the body of the wearer, Fig. 2. is a plan view of the supporting member, Fig. 3. is a plan view of the pad, Fig. 4. is a plan view of the sack, Fig. 5. is a transverse sectional view of the bandage assembled, and Fig. 6. is a view showing the bandage applied to a figure.

In the drawings the numeral 1, designates a supporting member, 2 a pad adapted to be disposed on the member, and 3 a sack or pocket adapted to be disposed on the pad.

The member 1 is formed of a suitable fabric in two layers separated by an inclosed padding 4 of absorbent cotton or other suitable material gradually reduced in thickness toward the outer edges as shown in Fig. 5.

The layers along their edges are suitably

bound together by a tape 5 or the like secured or sewed to the fabric. The particular shape of the supporting member is of great importance and it will be noted that it has a broad intermediate portion 6 from which a gradually tapered rear portion 7 extends and terminates in a loop 8. The member forward of the intermediate portion is divided into two outwardly flared tongues 9 gradually tapered toward their outer ends. The tapes 5 are continued along the outer sides of the tongues and extended to form elongated body engaging and supporting straps 10.

The intermediate portion 6 of the member is stitched through with lines of stitches 11 crossing each other at an angle and extending diagonally across the intermediate portion. The said portion is also formed with a dart 12 extending inward from the front end. These features are also of great importance for the reason that they cause the member to properly curve and adjust itself to the body of the wearer, and further the stitching 11, prevents the member from wrinkling or becoming "stringy" and at the same time causes it to retain its shape. At the rear end of the intermediate portion a central loop 13 is secured while at the opposite end of the said portion, loops 14 are provided at the sides and a loop 15 in the center.

The pad 2 is disposed on the intermediate portion 6 of the supporting member and it has a construction similar to the said portion, being formed of layers of rubber sheeting or the like bound with tape 16 and having an inclosed padding 17 of absorbent cotton or the like. This pad is shorter in length than the intermediate portion 6 and has a rounded point at its rear end, while its forward end is broad and blunt. A dart 18 is also formed in the pad so that it will have all of the self adjusting and shape retaining features of the supporting member.

The pad is removably held on the supporting member by tabs 19 at each end adapted to be tied into the loops 14 and 15. This arrangement obviates the use of safety pins or other metallic fastenings and permits the pad and supporting member to be washed separately which is necessary owing to the fact that the rubber sheeting cannot be immersed in very hot water.

The sack or pocket 3 is disposed on the 110

pad and is both shorter in length and less in width than the pad. This sack is elliptical in shape, being bound along its edges with tape 20 and provided at each end with tabs 21 adapted to be tied into the loops 13 and 5 15. In the central portion of the sack an opening or mouth 22 is provided. At this point I wish to call attention to the longitudinal curvature of the sack which is obtained by cutting out portions of the fabric 10 at each side of the opening and stitching the portions together at 23 causing the sack to have a general concavo-convex shape from end to end.

15 The shape of the sack causes it to readily adapt itself to the contour with which it is brought into contact. It is to be noted that the tabs 21 are at each end of the longitudinal center of the sack and are fastened to the loops 13 and 15 at the longitudinal center 20 of the supporting member whereby the sack is allowed a limited swinging movement on the pad 2 so that the sack more readily adjusts itself to position. A filling 25 24 of medicated absorbent cotton is deposited in the sack so as to be thickest at the opening, 23. This cotton can be removed and fresh cotton substituted when desired.

The manner of fastening and supporting 30 the bandage on the body of the wearer is one of the important features of the invention. The straps 10 before stated are continuations of the tapes 5. These straps have sufficient length to each pass substantially 35 entirely around the body of the wearer and have their free ends tied together in a knot at the front. The bandage is positioned as indicated in the drawings with the tongues 9 in front and the portion 7 in back. The 40 back portion 7 extends so that its loop 8 terminates just below the waist line of the wearer. The tongues 9 lie to each side of the front of the body and owing to their flaring construction and flexibility fit the 45 contour of the part to which they are applied. This is of importance as it obviates all wrinkles or protrusions and the liability of the bandage showing under the clothing.

In fastening the bandage to the body, the 50 straps are carried on each side of the waist and passed through the loop 8 at the back, one strap being continued around the body on the waist line to the right and the other to the left. The straps are drawn sufficiently taut to draw the supporting member 55 into close contact with the body especially at the front, but loose enough for comfort. The free ends of the straps are then passed through ring-loops 25 on the inner edges of 60 tongues near their ends, and then tied together in front below the waist line of the wearer. These loops 25 support the ends of the tongues and prevent them from falling down and the bandage losing its position.

65 It will be observed that the straps are sup-

ported on the hips of the wearer and no strain or supporting action is sustained by the clothing of the wearer. The strap arrangement in connection with the loops causes the bandage to be self adjusting and 70 to accommodate itself to the various positions assumed by the wearer. The total absence of safety pins or other metallic fastenings or any stiff or unyielding parts should be noted.

75 This bandage may be used in various ways and at times the sack may be omitted.

I wish to call attention to the fact that the padding 4 of fibrous material is gradually reduced in thickness toward its outer 80 edges to make the member 1 more pliable and comfortable along its sides.

What I claim is:

1. In a bandage, a supporting member having a diagonally stitched intermediate 85 portion with a tapered portion at one end and separated tongues terminating in fastening straps at the other end, a pad of water-proof material disposed on the stitched intermediate portion of the member, the member having provision for fastening the pad thereto, and a sack disposed on the pad and having an opening for receiving a filling of fibrous material.

2. In a bandage, a supporting member 95 having an intermediate portion provided with diagonal cross stitching and a central dart whereby said portion is shaped and prevented from wrinkling, the member having a tapered portion at one end and separated tongues at the other end, the tongues terminating in elongated fastening straps, a pad of water-proof material having diagonal cross stitching and a dart whereby the pad is shaped and prevented from wrinkling, the pad being removably attached to the supporting member over the intermediate portion thereof, and a sack having an opening and provided with darts on each side whereby the sack is curved, the sack 100 being disposed on the pad and removably attached to the supporting member.

3. In a bandage, supporting member having an intermediate padded portion stitched through with diagonal stitching in lines crossing each other at an angle, loops attached to the ends of the intermediate portion, a tapered back portion extending from end of the intermediate portion and provided at its outer end with a loop, diverging and tapered tongues extending from the opposite end of the intermediate portion and each provided with a loop near its outer end, elongated fastening straps extending from the ends of the tongue adapted to pass through the loop of the back portion and the loops of the tongues about the body of the wearer and have their free ends fastened together, a pad of water-proof material 115 stitched diagonally and provided with tabs 120 125 130

to engage the loops of the intermediate portion of the member, and a sack provided with tabs for engaging loops of the intermediate portion of the member, the sack having a concavo-convex shape and provided with an opening to expose a filling of fibrous material.

In testimony whereof I have signed my name to this specification in the presence of two subscribing witnesses.

IDA M. ARGO.
